United States Patent Office

Des. 184,622
Patented Mar. 17, 1959

184,622

SEMITRAILER

Wetmore Hodges, Jr., Palo Alto, and William H. Moranda,
Mountain View, Calif.

Application May 3, 1957, Serial No. 46,007

Term of patent 14 years

(Cl. D14—3)

Fig. 1 is a side elevational view of a semitrailer incorporating the design of our invention.

Fig. 2 is a top plan view.

Fig. 3 is a front elevational view.

Fig. 4 is a perspective view.

The characteristic features of our design for a semitrailer disclosed reside in the bifurcated hitch portions as shown.

We claim:

The ornamental design for a semitrailer, substantially as shown and described.
